Primary Examiner—Paula A. Mortimer
Attorney, Agent, or Firm—Todd N. Hathaway[57] **CLAIM**

The ornamental design for a window blind storage clip, as shown and described.

DESCRIPTION

FIG. 1 is a front perspective view of a window blind storage clip showing my new design;
 FIG. 2 is a front elevational view thereof;
 FIG. 3 is a top plan view thereof;
 FIG. 4 is a left side elevational view thereof;
 FIG. 5 is a right side elevational view thereof; and,
 FIG. 6 is a front elevational view thereof, the broken line showing of the window blind control rod and adjustment cord is for illustrative purposes only and forms no part of the claimed design.
